UNITED STATES PATENT OFFICE.

JAMES V. WASHBURN, OF FULTON, NEW YORK.

LUBRICATING ATTACHMENT.

1,267,610.

Specification of Letters Patent. Patented May 28, 1918.

Application filed April 21, 1914. Serial No. 833,422.

To all whom it may concern:

Be it known that I, JAMES V. WASHBURN, a citizen of the United States, residing at Fulton, in the county of Oswego and State of New York, have invented an Improvement in Lubricator Attachments for Machines for Opening Envelops, of which the following is a specification.

My invention relates to oiling or lubricator attachments for machines for opening envelopes, and particularly to that class of such machines employing a rotary cutting cylinder and a shear plate.

In so far as I am aware, this character of machine has not heretofore been provided with any means for oiling or lubricating the cutting cylinder or knife edges, and in practice it is found that, in the absence of such means, there is undue wear on the contacting parts, and a grinding sound is often produced when the machines are in operation.

The object of my present invention is to overcome these difficulties, and in carrying out my invention I employ a housing arranged horizontally extending parallel with the cutting cylinder its entire length, provided with ears or end pieces, by which it is connected to the machine, preferably to the shaft upon which the cutting cylinder is mounted; this housing has a longitudinal channel filled with a fibrous or porous material, capable of absorbing a lubricating substance.

The details of construction and operation of my invention are hereinafter more particularly described.

In the accompanying drawings, Figure 1 is a side elevation of my improved oiling device.

Fig. 2 is a longitudinal section of Fig. 1. Fig. 3 is a plan view.

Fig. 4 is an inverted plan view of the housing, the filling or absorbent material being removed for clearness of illustration.

Fig. 5 is a cross section of the device on the broken line y, y , of Fig. 1.

Fig. 6 is a section of one end of the lubricator, illustrating the ears attached to the housing by means of rivets.

Figs. 7, 8 and 9 are perspective views of one of the ears or end pieces detached, showing modifications therein.

Fig. 10 is a front elevation of a machine for opening envelopes, showing my improved lubricating device attached thereto.

Fig. 11 illustrates the manner in which the housing and its ears or end pieces may be cut

out of one piece of metal and bent or pressed into shape.

Fig. 12 is an elevation of one end of the machine, showing a modified form of attachment thereto of the lubricator, the base of the machine being in section, and

Fig. 13 is a view similar to Fig. 5, but showing the side walls of the housing slightly converged to clamp the absorbent material between them.

Similar reference characters indicate like parts throughout the several views.

This invention comprises a frame, a cylindrical cutter carried by the frame and having a lengthwise cutting edge, a lubricator attachment comprising an elongated housing extending lengthwise of the barrel of the cutter adjacent the same and absorbent material carried by the housing and exposed on the side thereof adjacent the periphery of the cutter in position to engage the periphery of the cutter, and supporting means at the ends of the cutter arranged to support the housing so that the housing moves with the cutter and permits the cutter to rock relatively to the housing.

1 indicates an elongated housing. 2, 2, are the dependent ears or end pieces secured to or made integral with the housing 1.

3 indicates the longitudinal channel in the housing, and 4 is the absorbent material filling said channel and extending an appreciable distance below the bottom thereof. 5 indicates spaced oil-cups in the top of the housing.

I prefer to make the housing 1 and its dependent end pieces 2, of metal, but they may be formed of any suitable material. The filling 4 is preferably felt, but it may consist of any fibrous or porous material capable of absorbing a lubricating substance.

The housing is preferably made of one piece, but it is obvious that it may be composed of two or more sections joined by solder or in any suitable manner.

The end pieces 2 may be secured to the housing in any suitable manner, but in the preferred form I make the end pieces 2 separate from the housing and provide each end piece with a right angled projection 6 at the top. The top of the housing at each end is formed with a recess or embossment 24, into which the right angled projections 6 on the end pieces fit in such a manner that their under surfaces are flush with the under surface of the top of the housing. These end pieces are secured in said re-

cesses in any suitable manner, preferably by solder, or by rivets 25.

The oil cups 5 on the top of the housing, are formed by making spaced perforations 5 and punching up the surrounding metal from the under side and upsetting the same upon the top of the housing. This leaves the under surface of the top uniform, without any depression or unevenness its entire 10 length, so that the filling material 4 may have an even bearing both at its top and bottom.

If desired, as before remarked, the housing 1 and its dependent ears 2 may be formed integral, and I have illustrated in Fig. 11, a blank out of which the same may be cut and bent to shape on the dotted lines 7, 8, 9 and 10.

The sides of the housing may be slightly 20 converged or bent toward each other at the bottom, their entire length, so as to clamp the absorbent material within the housing, as illustrated in Fig. 13, but I prefer that they be straight vertically, so as to be separated an equal distance from top to bottom, as it is not necessary that the absorbent material be clamped tightly within the channel. This preferred form is shown most clearly in Fig. 5. The absorbent material 30 projects somewhat below the housing and contacts with the cutting cylinder of the machine, as shown in Figs. 10 and 12.

The ears or dependent end pieces 2 are the means by which the lubricating device is 35 attached to the machine. In the preferred form I provide each end piece with an opening 11, through which the ends of the shaft 15 upon which the cutting cylinder of the machine is mounted pass.

In Fig. 10 of the drawing, I have illustrated my improved lubricating device attached in this manner to a machine. In this figure, 12 indicates the base of the machine. 13, 13, are uprights located respectively at 45 or adjacent each end of the base.

14 is a steel cutting cylinder mounted upon a shaft 15, the ends of which are journaled in the uprights 13, by which the cutting cylinder is supported. 16 represents 50 the operating lever secured to said shaft at one end by means of which the cutting cylinder is rotated.

The cutting cylinder 14 is provided with a longitudinal and inclined cutting edge 17. 55 18 indicates a horizontal steel shear-plate having a cutting edge which comes below the axis of the cutting cylinder, whereby the rotation of the cylinder will sever the edge of an envelop laid upon the shear-plate in 60 alignment with its cutting edge. The ends of the shear-plate 18 rest upon supports 19, one on each end of the base 12 forward of the uprights 13.

The shear-plate is adapted to slide upon 65 the supports 19.

Secured to each support 19 is a guide-plate 20, which prevents lateral displacement of the shear-plate. These guide-plates are each provided with an upturned portion 21, having openings in their ends adjacent the cutting cylinder in which the trunnions of a guide-roller 22 are supported.

Spiral springs 23, one end of each being secured to one of the supports 19 and its other end fixed to the shear-plate 18, tend to draw the cutting edge of the shear-plate toward the cutting cylinder 14.

It will be seen that when my improved lubricating device is attached to a machine of the character described, the end pieces 2 are connected with the shaft 15 upon which the cutting cylinder is mounted, between the ends of the cutting cylinder and the uprights 13, in which the ends of said shaft are journaled; this position prevents any lateral displacement of the lubricator.

In Fig. 5 of the drawing, I have illustrated the preferred shape of the ears or end pieces 2; the openings 11 for the reception of the ends of the shaft 15 being round, and the lower part of the ears cut away on one side leaving a downwardly projecting contact 27. Upon depressing the lever 16 the frictional contact of the felt or absorbent material 4, upon the surface of the cutting cylinder 14, will carry the housing forward until it contacts with the upturned portions 21 on the guide plates 20, and the same frictional contact will cause the housing to return to a vertical position on the upward movement of the lever, but its further backward movement is prevented by the contact points 27, on the ears 2, coming against the pins or studs 28 on the up- 105 rights 19.

However, if desired, the ears or end pieces 2, may be formed as shown in either Figs. 7, 8 and 9.

In the form shown in Fig. 7, the openings 11 are somewhat elongated vertically, so that the housing may have a slight vertical movement, while the lower ends of the ears are provided with an open-ended slot 29, which fits over the pins or studs 28 and prevents 115 lateral movement of the housing.

In the form shown in Fig. 8, the ears are provided with right-angled arms 30 to bear against the sides of the uprights 13, thereby preventing lateral movement of the housing. 120

In the form shown in Fig. 9, the lower ends of the ears 2 are rounded so that in shipping the machines, the housing may be turned back to rest upon the base 1, where it will be in a position least liable to injury. 125

Where the ears 2 are formed, as shown in the modifications Figs. 8 and 9, the pins or studs 28 are dispensed with.

While I prefer that the lubricator be attached to the machine in the manner above 130

described, it may be connected in the manner shown in Fig. 12, in which case the openings 11 in the ears are dispensed with, and the lower parts of the ears are bent outwardly and shaped to fit over the tops of the uprights 13, to which they may be fastened in any suitable manner, preferably by screws 31.

I claim as my invention:

10 1. The combination of a machine including a frame formed with bearings, a cylindrical cutter mounted in the bearings, and having a lengthwise cutting edge, a lubricator attachment comprising an elongated 15 housing extending lengthwise of the periphery of the cutter adjacent the same, an absorbent material carried by the housing and exposed on the side thereof adjacent the periphery of the cutter in position to engage 20 the periphery of the cutter, and supporting means at the ends of the housing, said means being mounted upon the axis of the cutter, and means for moving the cutter about its axis, substantially as and for the purpose 25 described.

2. The combination of a machine including a frame formed with bearings, a cylindrical cutter mounted in the bearings and having a lengthwise cutting edge, a lubricator attachment comprising an elongated 30 housing extending lengthwise of the periphery of the cutter adjacent the same, an absorbent material carried by the housing and exposed on the side thereof adjacent the periphery of the cutter in position to engage 35 the periphery of the cutter and supporting means at the ends of the housing, said means being mounted upon the axis of the cutter, the supporting means being located between 40 the ends of the cylinder and the bearings for said cylinder, and means for moving the cutter about its axis, substantially as and for the purpose specified.

3. The combination of a machine comprising a frame formed with bearings, a cylindrical cutter movable about an axis and having axles at its end journaled in the bearings, and a lubricant attachment comprising an elongated housing in the form of a 45 channel extending lengthwise of the cutter adjacent its periphery and having its open side opposed to the cutter and of less width than the diameter of the cutter, and means for supporting the channel on the axis of 50 the cutter and permitting movement thereof relatively to the cutter, substantially as and for the purpose set forth.

4. The combination of a machine comprising a frame, a cylindrical cutter movable 60 about an axis and having axles at its end journaled in the frame, and a lubricant attachment comprising an elongated housing in the form of a channel extending length-

wise of the cutter adjacent the same, and having its open side opposed to the cutter 65 and of less width than the diameter of the cutter, and means for supporting the channel and permitting relative rocking movement thereof with and relatively to the cutter, substantially as and for the purpose described. 70

5. The combination of a machine comprising a frame, a cylindrical cutter movable about an axis and having axles at its end journaled in the frame, and a lubricant attachment comprising an elongated housing in the form of a channel extending lengthwise of the cutter adjacent the same and having its open side opposed to the cutter and of less width than the diameter of the 75 cutter, means for supporting the channel and permitting rocking movement thereof with and relatively to the cutter, said means being mounted upon the axles of the cutter, said attachment being movable about the 80 axis of the cutter by frictional contact thereof with the cutter, means for limiting such movement, and means for moving the cutter a greater distance about its axis, than the lubricator attachment is capable of moving 85 therewith, substantially as and for the purpose specified.

6. The combination of a machine comprising a frame formed with bearings, a cylindrical cutter movable about an axis and having 90 axles at its ends journaled in the bearings, and a lubricant attachment comprising an elongated housing extending the length of the cutting edge of said cutter and being in the form of a channel flaving its 95 open side opposed to the periphery of the cutter, absorbent material in the channel and resting on the periphery of the cutter, and ears at the ends of the housing extending at an angle thereto and beyond the open 100 side of the channel, the ears being mounted upon the axles of the cutter, substantially 105 as and for the purpose set forth.

7. A device for lubricating the cutter cylinder of machines of the character described 110 comprising an elongated housing open at its bottom and extending lengthwise of the cylinder, the full length of the cutting edge, means at the ends of the housing for attachment to the machine, and an absorbent 115 material within the housing projecting through the open bottom thereof into engagement with the cylinder, and means for rotating the cylinder, substantially as and for the purpose described. 120

Signed by me this 11th day of April, 1914.

JAMES V. WASHBURNE.
